(57) **CLAIM**

The ornamental design for a safety cover for a hitch, as shown and described.

DESCRIPTION

FIG. 1 is a top plan view of a first embodiment of the safety cover for hitch showing one embodiment of our new design; FIG. 2 is a bottom plan view of the design of the safety cover for hitch;

FIG. 3 is a side elevation view of the design of the safety cover for hitch;

FIG. 4 is another side elevation view of the design of the safety cover for hitch;

FIG. 5 is another side elevation view of the design of the safety cover for hitch;

FIG. 6 is yet another side elevation view of the design of the safety cover for hitch; and,

FIG. 7 is a top plan view of a second embodiment of the safety cover for hitch.

The broken line showing of multiple logos is included for the purpose of illustrating environment and forms no part of the claimed design.
